Term of patent 14 years

Int. Cl. D30—01

U.S. Cl. D30—2

FIG. 1

FIG. 1 is a front elevational view of a wire mesh panel for poultry cages embodying my new design;

FIG. 2 is a rear elevational view of the panel shown in FIG. 1; and

FIGS. 3 and 4 are end and top views respectively, of the panel shown in FIGS. 1 and 2.

This application is a continuation-in-part of my co-pending application Ser. No. D. 10,409, filed Feb. 1, 1968, and now abandoned.

I claim:

The ornamental design for a wire mesh panel for poultry cages, as shown.
